H. Braunhoff's Design for Trunk

No. 1,996.

Patented Nov. 4, 1874.

Henry Braunholtz, of New York, N.Y.

DES. 1996

Letters Patent No. 1996. Dated Nov. 8th 1864.

Design for a Trunk Cover.

The schedule referred to in these Letters Patent and making part of the same.

Is all whom it may concern:

Be it known that I, Henry Braunholtz, of No. 176, Chatham Sq., in the City, County and State of New York, have invented a new and ornamental Design for Trunk Covers; and I do hereby declare that the following is a full, clear and exact description thereof, which will enable those skilled in the art to make and use the same, reference being had to the accompanying drawing forming part of this specification.

The drawing represents a trunk cover ornamented with my improved design.

This design consists of a border of double lines one being heavy and the other light and drawn to enclose a rectilinear space which is divided off in a number of compartments by horizontal and vertical partitions, each partition being composed of double lines, one heavy and the other light parallel to the border lines, the size of the whole ornament and of the various squares being dependent on the size of the trunk which is to be covered.

A represents the border which is composed of two lines, a, b, one heavy and the other light, as shown, and which is made to enclose a rectilinear space B. The space is divided off into a number of compartments C, by the horizontal partitions D and the vertical partitions E. All these partitions are composed of double

DES. 1996

2 vertical partitions B. All these partitions are composed of double lines c. d. one heavy and the other light, similar to the lines a. b. which compose the border A.

The horizontal partitions extend clear through from one side of the border to the other and the various distances intervening between them depend upon the area and height of the trunk to be covered.

Claim is now and desire to secure by Letters Patent A design for trunk covering as shown and described.
